UNITED STATES PATENT OFFICE.

NICOLA PAPA, OF UTICA, NEW YORK.

ELECTRIC-LIGHT APPARATUS.

1,240,770.

Specification of Letters Patent. Patented Sept. 18, 1917.

Application filed March 14, 1916. Serial No. 34,122.

To all whom it may concern:

Be it known that I, NICOLA PAPA, a citizen of the United States, residing at Utica, in the county of Oneida and State of New York, have invented new and useful Improvements in Electric-Light Apparatus, of which the following is a specification.

This invention is an improved electric light apparatus adapted for use as a search light and also adapted for use as a blinding light, as hereinafter described and claimed.

The object of the invention is to provide an electric light and means to cause the same to project either a steady beam of light or to project a series of twinkling or rapidly successive beams which have a blinding effect on persons in front of the light, and so that the apparatus may be used either as an ordinary search light or as a blinding light in time of war.

The invention consists in the features of construction, combination, and arrangement of devices, hereinafter described and claimed.

25 In the accompanying drawings:

Figure 1 is a sectional view of an electric light apparatus constructed in accordance with my invention.

Fig. 2 is a detail elevation of the twinkling or intermittently acting switch.

Fig. 3 is a diagram in which the electric circuits are traced.

Fig. 4 is a sectional view of a modified form of the electric light apparatus in which a manually operated intermittently acting switch is employed.

In the embodiment of the invention here shown, a suitable casing 1 is provided in the front end of which is a lens 2. A reflector 3 is arranged in the casing, in rear of the lens and a cluster of electric lamps 4 are arranged in the center of the reflector. Conductors 5, 6, are connected to the electric lamps and to a source of electricity conventionally indicated at 7 in Fig. 3 and the conductor 6 is provided with a switch 8, which I will here term a constant switch, and which when closed causes the electric lamp to be supplied with current and to project a steady light which enables the apparatus to be used as a search light.

I also provide an intermittently acting switch 9 which is here shown as comprising a revoluble conducting member 10 having three radially arranged conducting arms 11. The intermittently acting switch also

includes a pair of spaced fixed contact points 12, 12' which are here shown as secured to and insulated from a supporting arch bracket 13, the insulation of said fixed contact points being indicated at 14. The point 12 is connected by a conducting wire 15 to the conductor 6 of the electric light circuit, and said conductor 15 includes spaced contact points 16.

An electric motor 17 is connected by a conductor 18 to the conductor 5 and by a conductor 19 to the conductor 15, said conductor 19 being provided with contact points 20. The revoluble switch element 10 is mounted on and insulated from the shaft 21 of the motor, the insulation being indicated at 22 in Fig. 2. A double knife switch 23 is provided, one member 24 of which is adapted to complete a circuit between the points 16, the member 25 of said switch being adapted to complete a circuit through the points 20.

When the switch 8 is opened, and the switch 23 is closed, the motor and the intermittently acting switch 9 are together with the electric light or lights 4 included in multiple arc with the electric circuit, hence the motor is constantly operated, thus causing the member 10 of the switch 9 to rotate and at each rotation of said member 10 its arms 11 in pairs, intermittently close and break the circuit by contacting with and moving over the points 12, 12', so that the light or lights 4 are caused to twinkle and project intermittent rays of light which have a blinding effect and hence prevent the locality of the apparatus from being visually distinguished.

Hence the apparatus is adapted to be used either as a search light or as a blinding light, at will.

The apparatus is shown in Fig. 1 as connected by a ball and socket joint 26, to a suitable supporting standard 27 and the socket member of the joint is indicated as provided with a clamping screw 28 so that the apparatus may be secured in any desired adjusted position.

In Fig. 4 of the drawings, I show a modified form of my improved light apparatus in which the electric motor is dispensed with and the revoluble element of the intermittently acting switch is carried by a shaft 29 which is mounted in a bearing 30 in one side of the casing and is provided with a hand crank 31. In this figure, the electric

lights are indicated at 4^a, the battery at 7^a and the constant switch at 8^a.

It is believed that, from the foregoing description, the nature and advantages of the invention will be readily apparent without requiring a more extended explanation and therefore the same has been omitted. However, I desire to have it understood that various changes in the construction and arrangement of parts may be resorted to when desired as fall within the scope of the appended claim.

Having described the invention, what is claimed is:

15 An apparatus of the class described, a circuit including a light and a switch, a shunt of said circuit including an electric

motor, a subshunt excluding the motor and including a motor driven intermittently acting switch, and switches to open and close the shunt and subshunts, whereby when the first named switch is closed and the last named switches are open, the light will operate continuously, and when the first named switch is open and the last named switches are closed the light will flash intermittently.

In testimony whereof, I affix my signature in presence of witnesses.

NICOLA PAPA.
